UNITED STATES PATENT OFFICE.

CHARLES A. MOORE, OF ST. PAUL, MINNESOTA.

COMBINED TRAP AND SEAL.

1,290,636.

Specification of Letters Patent. Patented Jan. 7, 1919.

Application filed March 23, 1914, Serial No. 826,779. Renewed May 18, 1918. Serial No. 235,394.

To all whom it may concern:

Be it known that I, CHARLES A. MOORE, a citizen of the United States, residing at St. Paul, in the county of Ramsey and State of Minnesota, have invented a new and useful Improvement in Combined Traps and Seals, of which the following is a specification.

My invention relates to a combined trap and seal for catching drip and liquid from 10 an ice bunker and the floor of a cooling room, refrigerator or refrigerator car. The primary object is to seal the drain passage and prevent air from entering the cooling chamber in winter time when no ice is employed 15 in the cooling chamber, so that the cooling chamber may be used for heating purposes and to permit the egress of water through the drain in summer time without admitting warm air.

20 In the accompanying drawing forming part of this specification, Figure 1 is a detail in section taken on the line X—X, Fig. 3, and showing my invention in use on a portion of a refrigerator car, the combined 25 trap and seal being illustrated in open position; Fig. 2 is a view similar to Fig. 1 showing the combined trap and seal closed, and Fig. 3 is another detail partly in section taken on the line Y—Y, Fig. 2, and looking 30 at the side of the car and at the front of the combined trap and seal.

In the drawing A indicates a detail of a refrigerator car, 2 representing a portion of the side wall, 3 a portion of the floor and 35 4 a sill supporting the floor and side wall. 5 represents a portion of the drain pipe which is adapted to lead down from an ice bunker and 6 represents a drain pipe passing downwardly through and projecting below the sill 4 of the car, the upper end of 40 said pipe 6 communicating with the interior of the car and receiving the lower end of drain pipe 5, whereby the drain 6 is adapted to conduct any drip or water from the drain 45 pipe and floor of the car to the outer atmosphere. Mounted upon the sill 4 by a hinged connection 7 is a frame receptacle 8 which is open at its upper end and closed at its lower end. This receptacle has a 50 metal lining forming a water tight cup 9 which extends over the rim of the receptacle and down over its front wall, being nailed or otherwise secured in place. In closed condition the receptacle is swung up with its 55 rim tightly pressing against a surface plate 10 which is nailed or otherwise secured to

the lower surface of the sill 4. In this position the drain 6 is sealed substantially from the outer atmosphere by the receptacle that is when no water in liquid or frozen condition 60 is in the receptacle. The free or front side of the receptacle is provided with a clasp 11 which is secured thereto by means of the bolt 12, said clasp being formed with a forwardly projecting arm 13, which can be used 65 as a handle to raise or lower the receptacle. This arm is bifurcated and straddles a depending support 14 which is secured to the sill 4 by the bolts 15. This support has a pair of openings 16 and 17 through which 70 a pin 18 having two spring arms such as 19 is adapted to be passed to engage the arm 13 between them and hold the receptacle in either open or closed position. One of the arms 19 of the pin 18 is crimped to prevent 75 it from becoming unintentionally detached from locking position when in use. A chain 21 secured to the sill and the lock pin 18 serves to prevent the pin from being lost when the receptacle is allowed to hang in 80 unsupported position below the drain. In use when it is desired to seal the drain 6, it is swung up against the plate 10 and locked by the pin passing through the opening 16. When in use to allow water passing downwardly through the drain 6 and prevent air 85 from entering the cooling chamber, the receptacle is locked in lowered position as illustrated in Fig. 1 by inserting the pin through the opening 17 in the support 14. When it 90 is desired to clean the drain the pin is removed from the support and the drain swung downwardly below the car.

In accordance with the patent statutes I have described the principles of operation of 95 my invention together with the apparatus which I now consider to represent the best embodiment thereof, but I desire to have it understood that the construction shown is only illustrative and that the invention can 100 be carried out by other means and applied to uses other than those above set forth within the scope of the following claims.

Having described my invention, what I claim as new and desire to protect by Letters Patent is:—

1. In combination with a drain pipe and its support, a receptacle into which the lower end of said drain pipe projects, said receptacle being hinged to said support and adapted to swing upwardly against its lower surface to seal said drain pipe and to be swung

- down into a position to form a water trap around said drain pipe and means for holding said receptacle in either closed position against said support or in said lowered position.
2. In combination with a support having a drain pipe extending below the same, a receptacle hinged to said support and adapted to swing upwardly against said support to seal said drain pipe, to be moved down into lowered position to form a trap surrounding the lower end of said drain pipe or to swing backwardly entirely free of the drain pipe, a locking element projecting from the free side of said pipe, a member extending downwardly from said support provided with superimposed openings and a lock pin adapted to be inserted through said openings to

engage said locking element to hold said receptacle in either closed position to seal 20 said drain pipe when said receptacle is empty or in open position to form a water trap.

3. In combination with a drain duct and a support adjacent to said duct, a receptacle into which the lower end of said duct projects, said receptacle being movably supported to close against said support and seal 25 said duct or to assume a position forming a liquid trap for said duct.

In testimony whereof I have signed my 30 name to this specification in the presence of two subscribing witnesses.

CHARLES A. MOORE.
